UNITED STATES PATENT OFFICE.

TONY CRAVELONE AND CARL MARTELLO, OF ANACONDA, MONTANA.

AUTOMATIC TRAIN-PIPE CONNECTOR.

1,392,121.

Specification of Letters Patent. Patented Sept. 27, 1921.

Application filed February 10, 1920. Serial No. 357,654.

To all whom it may concern:

Be it known that we, TONY CRAVELONE and CARL MARTELLO, citizens of Italy, but both having taken out first papers for citizenship 5 in the United States of America, residing at Anaconda, in the county of Deerlodge and State of Montana, have invented new and useful Improvements in Automatic Train-Pipe Connectors, of which the following is a specification.

The object of the invention is to provide a means for accomplishing the automatic coupling of the sections or elements of a train pipe line simultaneously with the engagement of the car coupling members and of correspondingly and simultaneously disconnecting the members of the train pipe as carried by the several cars of a train as an incident to the uncoupling or detachment 20 of a car under such conditions as to avoid the necessity of the separate or independent manipulation of coupling means as through manual intervention, under such conditions as to permit of the gradual or gradated admission of pressure to the train line section of a car which is being coupled, and also under such conditions as to permit retaining pressure in the train pipe section 25 of a disconnected car after the disengagement of the car coupling members to the end that the air brake operating pressure on the car thus disconnected or cut out may be indefinitely retained or gradually reduced by bleeding, as may be preferred; and with 30 these objects in view the invention consists in a construction and combination of parts of which preferred embodiments are illustrated in the accompanying drawings, it being understood that changes in form, proportion and details may be resorted to, within the scope of the appended claims without departing from the principles involved.

In the drawings:

Figure 1 is a plan view of the apparatus.

Fig. 2 is a side view showing the preferred location of the train pipe connector beneath the car coupler.

Fig. 3 is a longitudinal section on the plane indicated by the line 3-3 of Fig. 1.

Fig. 4 is a horizontal section on the plane indicated by the line 4-4 of Fig. 2.

Fig. 5 is a plan view partly in section on the plane 5-5 of Fig. 2 showing the impact 55 plunger in its repressed position to effect

the partial opening of the main and supplemental valves.

Fig. 6 is a side elevation of a construction showing a modified arrangement of the connector. 60

Fig. 7 is a horizontal section on the plane indicated by the line 7-7 of Fig. 6.

Fig. 8 is a detail horizontal section of one of the connector heads or members.

Fig. 9 is a detail section of the pressure 65 valve and operating piston cylinders with their related parts.

Fig. 10 is a detail section on the plane indicated by the line 10-10 of Fig. 7.

Fig. 11 is a detail view of the main train 70 pipe valve.

Fig. 12 is a transverse section on the plane indicated by the line 12-12 of Fig. 7.

Fig. 13 is a longitudinal sectional view 75 of the pressure valve forming an important feature of the invention.

Fig. 14 is a detail perspective view of the arm for operating the auxiliary valve forming a feature of the invention.

The apparatus is shown in operative relation with car coupling members 20 of the Janney or any other suitable or preferred type of which the heads should be provided, for example, with depending bars 21 for supporting frames 22, and consists essentially of the connector members 23 mounted in said frames and having rearwardly extending stems 24 upon which are arranged cushion springs 25 for relieving the jar incident to coupling, each of the heads having 80 an air channel 26 in communication permanently with the train pipe 27 by means of a suitable extension 28 which may for the purpose of permitting the yielding movement of the connector head be of flexible 85 construction, the connection between the train pipe and the air channel of each connector head being independent of the ordinary flexible coupling pipe 29 and coupler head 30 now in common use and controlled 90 by the manually operable air valve 31, to the end that this ordinary means of coupling the parts of a train pipe may be employed when both of the cars between which a connection is to be established are not provided with the connector forming the subject matter of this invention. 95

As the two members of the connector are complementary and similar in construction it will be sufficient to describe in detail only 100

105

110

one, with the preliminary explanation that the air channel 26 is intercepted at a convenient point in its length by a main cut-off valve 32, and terminates at the face of a jaw 33 in a yielding gasket 34, said jaw being opposed by a companion jaw 35 in which is mounted a yielding button 36 for engagement with a socket 37 in the complementary head when the jaw 33 of said complementary head is interposed between the jaws 33 and 35 of the first-named head, the said yielding button being actuated by a spring 38 which adapts it to be repressed sufficiently to allow the jaw 33 of the complementary head to be properly seated and then resumes its normal position to hold the jaws in interlocked relation so that the air passage 26 of one head is in operative communication with the corresponding passage of the complementary head. Obviously the disconnection of the connector heads may be effected by a longitudinal strain in opposite directions applied thereto incident to the separation of the cars by which they are respectively carried when the couplers of said cars are disengaged.

Mounted in each connector head for longitudinal movement relative thereto is a plunger 39 having an impact head 40 which projects into the throat 41 represented by the space between the opposing jaws 33-35 to the end that when the jaw 33 of the complementary connector head is introduced into the throat its forward end will contact with said plunger head and repress the latter against the impulse of a spring 42 which normally holds said plunger advanced. The plunger is operatively connected with an operating arm 43 of the main valve 32, which is normally held closed by means of the spring 42, as by having said plunger provided with a slot 45 which embraces the arm 43, to the end that the repression of the plunger serves to effect a partial opening of the main valve 32 to permit of the passage of air through the channel 26 to the terminal represented by the gasket 34.

Also in communication with the channel 26, beyond the main valve 32 or between the latter and the outlet gasket 34 is a branch passage 46 provided at an intermediate point with an auxiliary valve 47 and having connection with the casing 48 of a pressure valve 49 consisting, in the construction illustrated, of a piston normally held advanced, in opposition to air pressure admitted from the channel 46 by a spring 50 and serving to control an outlet 51 from said casing 48 to a passage 52 leading to one end of a piston cylinder 53 in which is mounted a piston 54 actuated in opposition to air pressure by a spring 55 and having a stem 56 connected with the arm 43 (or an equivalent arm) of the main valve as by a fork 57 to the end that air permitted to traverse the channel 26 by the partial opening of the main valve 32 and

passing through the branch 46 will repress the pressure valve 49 to expose the port 51 and thus admit air to the cylinder 53 and thereby cause the reversion of the piston 54 against the tendency of the spring 55 to complete the opening of the main valve 32.

The secondary or auxiliary valve 47 which is normally adapted to be in a closed position is adapted for actuation to open the branch passage 46 by the interlocking of the heads of the connector members, and to this end said valve is provided with an arm 58 arranged in the path of a dog 59 carried by the plunger 39 and adapted to receive an opening impulse by the reversion of said plunger incident to the engagement of the jaws of the complementary connector heads, said arm being arranged to terminally traverse a lifting cam 60 disposed on the connector head to the end that when the secondary valve has been moved to a sufficiently open position to permit of communication through the passage 46 to the pressure valve casing 48, the arm 58 will be lifted out of the path of the dog 59, so that further movement of the dog will cause it to pass under said arm 58. The further movement of said dog obviously is incidental to the movement of the arm 43 of the main valve due to the action of the piston 54, and the deflecting movement of the cam 60 is in opposition to a pressure spring 62 arranged upon a stem 63 which extends through a slot 64 in a bracket 65, said spring bearing against a washer or friction button 66 in contact with the bracket. A handle 67 is also employed in connection with the secondary valve to the end that when two cars are to be uncoupled, and it is desired that the application of brakes on a disconnected car shall not occur immediately due to the abrupt opening of the train line and the exhaust of pressure in the portion of the train pipe on the disconnected car, the secondary valve may be closed by hand. The closing movement of said secondary valve is limited by the contact of the arm 58 with a stop 68. The dog 59 is beveled at its rear or outer side to adapt it to pass under the arm 58 as the plunger 39 recedes due to the disengagement of the connector heads.

In order that the pressure in the piston cylinder 53 may be gradually exhausted after the disconnection of a car from the train there is provided in the pressure valve casing 48 a bleed port 90 which, when the pressure valve 49 is relieved of direct pressure from the air channel 26 and advances beyond the port 51, is brought into communication with the passage 52 leading from said piston cylinder, said vent 90 leading to the atmosphere.

Thus in operation the action incident to the engagement of the connector heads is to repress the plunger 39 to effect the partial

opening of the main valve 32 and also the opening of the secondary valve 47 if the latter is in its closed position, to the end that air pressure is permitted to pass through the 5 branch passage 46 to the pressure valve casting to establish communication with the piston cylinder 53 and the repressing of the piston, serving to further open the main valve 32 will permit the gradual equalization of 10 train pipe pressure in the connected car, and the parts will retain these set positions until the disconnection of the car occurs whereupon the reduction of pressure in the branch passage 46 will permit the pressure valve 49 15 to establish communication between the cylinder feed passage 52 and the vent 90 to bleed the piston cylinder 53 and allow the main valve to be closed by its actuating spring. On the rear end of the train from 20 which a car has been disconnected it is obviously desirable that the closing of the main valve shall occur immediately, and with this in view the secondary valve 47 at the rear end of the train should be permitted to re- 25 main open so that the exhaust of air from the exposed end of the passage 26 will allow the pressure valve 49 to immediately establish communication between the cylinder 53 and the atmosphere so that the piston 54 may 30 return promptly to its normal position under the action of its return spring 55, but as to the disconnected car, wherein it may be desirable to retain the train pipe pressure for a period to prevent the immediate appli- 35 cation of the brakes due to the sudden reduction of pressure in the train pipe, the precaution should be taken, before uncoupling the car, to close the secondary valve as hereinbefore noted, so that the leakage from the 40 cylinder 53 may be gradual, or so that the exhaust from the pressure valve casing through the branch passage 46 may be prevented.

In the modified construction illustrated in 45 Figs. 6 to 12 inclusive the essential parts hereinabove enumerated in connection with the preferred form of the device are embodied, including the connector heads 62' having the opposed jaws 63' and 64' with a pressure button 65' on the latter for engagement with a seat or socket 66' in the jaw 63' of the complementary head, the main air passage 67' controlled by the main valve 68', a plunger 69 for repressing by the complementary connector head to act through a fork 70 upon an arm 71 of the main valve to partly open the same, a branch passage 72 communicating with the main air passage 67 and having a secondary controlling valve 73, 50 a pressure valve casing 74 in communication with said branch passage 72 and containing a pressure valve 75 controlling a feed passage 76 in communication with a piston cylinder 77 in which is mounted a spring re- 55 pressed piston 78 of which the stem 79 is

provided with a fork 80 for engaging the arm 71 to complete the opening movement of the main valve 68'.

In this instance the secondary valve is adapted solely for manual operation or setting and is provided with a stem 81 having a crank arm 82 with which is connected a handle or grip 83 disposed at the side of the car so as to permit of the closing of said valve prior to the disconnection of the car by 70 which it is carried from the balance of the train, to retain the pressure in the valve casting 74 for reasons explained in connection with the form of the apparatus illustrated in Figs. 1 to 5 inclusive.

In order to insure the accurate interlocking of the heads and prevent displacement vertically thereof particularly in the operation of coupling, guide fingers 84 may be attached to the upper and lower surfaces of the 85 respective heads, said tongues having deflected extremities as indicated in Fig. 6, and yielding guide arms 85 also carried respectively by and longitudinally with said heads and adapted at their deflected free ends 86 90 for respective engagement with guide pins 87 projecting laterally from the opposing head, as clearly indicated in Fig. 7.

What is claimed is:

1. A train pipe connector having complementary heads provided with interlocking jaws, each head having an air passage in communication with the train pipe and terminating at the face of one of the jaws for registration with the terminal of the corresponding air passage of the complementary head, a main valve for controlling said air passage, means operable upon the engagement of the two heads to effect a partial opening of the said main valve, and means for completing the opening movement of said valve subsequent to the completion of the coupling operation of the heads.

2. A train pipe connector having complementary heads provided with interlocking jaws, each head having an air passage in communication with the train pipe and terminating at the face of one of the jaws for registration with the terminal of the corresponding air passage of the complementary head, a main valve for controlling said air passage, means operable upon the engagement of the two heads to effect a partial opening of the said main valve, and pressure actuated means controlled by the said main valve for effecting the complete opening of the latter.

3. A train pipe connector having complementary heads provided with interlocking jaws and each having an air passage in communication with the train pipe and terminating at the face of one of the jaws for registration with the terminal of the corresponding air passage of the complementary

head, a main valve for controlling said air passage, a plunger having an impact head in the path of the complemental coupler head and operatively connected with said valve for effecting a partial opening thereof, and pressure actuated means controlled by said main valve for effecting the complete opening of the latter.

4. A train pipe connector having complemental coupler heads provided with interlocking jaws and air passages in communication with the train pipe and adapted for terminal registration by the engagement of said jaws, each of said heads having a main valve for controlling its air passage, a plunger provided with an impact head for repression by the complemental head and operatively connected with said valve for effecting a partial opening thereof, a pressure valve exposed to train pipe pressure by the partial opening of said main valve, and a main valve operating piston having its cylinder provided with a train pipe pressure inlet controlled by said pressure valve.

5. A train pipe connector having complemental heads provided with interlocking jaws and air passages in communication with the train pipe for registration by the engagement of said jaws, each of said heads being provided with a main valve for controlling its air passage, a plunger operatively connected with said valve and actuatable to effect a partial opening thereof by the engagement of said jaws, a pressure valve having its casing in communication with the air passage and controlled by said main valve, a main valve operating piston, and feed and exhaust ports for the cylinder of the main valve operating piston controlled by said pressure valve.

6. A train pipe connector having complemental coupler heads provided with interlocking jaws and air passages in communication with the train pipe and adapted for registration by the engagement of said jaws, each of said heads having a main valve for controlling its air passage, an impact plunger operatively connected with said valve and actuatable by the engagement of the jaws of a complemental head to effect a partial opening of said valve, a main valve operating piston for effecting the complete opening movement of said main valve, a pressure valve for controlling the inlet port to the cylinder of said piston, a feed passage for the casing of said pressure valve in communication with the air passage of the head, and a secondary valve for said feed passage for controlling the admission of air to the pressure valve.

7. A train pipe connector having complemental coupler heads provided with interlocking jaws and air passages in communication with the train pipe and adapted for

registration by the engagement of said jaws, each of said heads having a main valve for controlling its air passage, an impact plunger operatively connected with said valve and actuatable by the engagement of the jaws of a complemental head to effect a partial opening of said valve, a main valve operating piston for effecting the complete opening movement of said main valve, a pressure valve for controlling the inlet port to the cylinder of said piston, a feed passage for the casing of said pressure valve in communication with the air passage of the head, and a secondary valve for said feed passage for controlling the admission of air to the pressure valve, and operatively connected with said plunger.

8. A train pipe connector having complemental coupler heads provided with interlocking jaws and air passages in communication with the train pipe and adapted for registration by the engagement of said jaws, each of said heads having a main valve for controlling its air passage, an impact plunger operatively connected with said valve and actuatable by the engagement of the jaws of a complemental head to effect a partial opening of said valve, a main valve operating piston for effecting the complete opening movement of said main valve, a pressure valve for controlling the inlet port to the cylinder of said piston, a feed passage for the casing of said pressure valve in communication with the air passage of the head, and a secondary valve for said feed passage for controlling the admission of air to the pressure valve, and means being provided for communicating opening movement to said secondary valve by the repression of said plunger.

9. A train pipe connector having complemental coupler heads provided with interlocking jaws and air passages in communication with the train pipe and adapted for registration by the engagement of said jaws, each of said heads having a main valve for controlling its air passage, an impact plunger operatively connected with said valve and actuatable by the engagement of the jaws of a complemental head to effect a partial opening of said valve, a main valve operating piston for effecting the complete opening movement of said main valve, a pressure valve for controlling the inlet port to the cylinder of said piston, a feed passage for the casing of said pressure valve in communication with the air passage of the head, and a secondary valve for said feed passage for controlling the admission of air to the pressure valve, said secondary valve having a yielding arm disposed, in the closed position of said valve, in the path of a dog on said plunger.

10. A train pipe connector having complemental coupler heads provided with inter-

locking jaws and air passages in communication with the train pipe and adapted for registration by the engagement of said jaws, each of said heads having a main valve for controlling its air passage, an impact plunger operatively connected with said valve and actuatable by the engagement of the jaws of a complementary head to effect a partial opening of said valve, a main valve operating piston for effecting the complete opening movement of said main valve, a pressure valve for controlling the inlet port to the cylinder of said piston, a feed passage for

the casing of said pressure valve in communication with the air passage of the head, 15 and a secondary valve for said feed passage for controlling the admission of air to the pressure valve, said secondary valve being provided with an opening arm, and said plunger with a dog for engagement therewith, and a cam for deflecting said arm from the path of the dog. 20

In testimony whereof we affix our signatures.

TONY CRAVELONE.
CARL MARTELLO.
